ABSTRACT OF THE DISCLOSURE

Carbamides of the formula

wherein R' is selected from the group consisting of hydrocarbyl and substituted hydrocarbyl having up to four substituents, wherein the hydrocarbyl is selected from the group consisting of primary alkyl of not more than 12 carbon atoms, benzyl and phenyl, and wherein the substituents on the hydrocarbyl are selected from the group consisting of nitro, chlorine, bromine, alkoxy of not more than 4 carbon atoms, alkyl of not more than 4 carbon atoms and phenyl; and R is selected from the group consisting of hydrocarbyl and substituted hydrocarbyl having up to four substituents, wherein the hydrocarbyl is selected from the group consisting of alkyl of not more than 12 carbon atoms, alkenyl of not more than 12 carbon atoms, cycloaliphatic having at least 4 and not more than 8 carbon atoms, benzyl and phenyl, and wherein the substituents on the hydrocarbyl are selected from the group consisting of chlorine, bromine, nitro, alkyl of not more than 4 carbon atoms, alkoxy of not more than 4 carbon atoms and phenyl are useful in the control of plant systems and pathogenic microorganisms.

This application is a continuation-in-part of application Ser. No. 310,847, filed Sept. 23, 1963, now abandoned.

This invention relates to novel carbamides and to processes for their preparation. The carbamides of this invention have biological toxicant properties and can be used to control the growth of plant systems and to control pathogenic microorganisms.

The carbamides of this invention are prepared by a process which comprises reacting an N-substituted carbamic acid ester with oxalyl chloride in accordance with the following representative synthesis:

wherein R' is selected from the group consisting of hydrocarbyl and substituted hydrocarbyl having up to four substituents, wherein the hydrocarbyl is selected from the group consisting of primary alkyl of not more than 12 carbon atoms, benzyl and phenyl, and wherein the substituents on the hydrocarbyl are selected from the group

2

consisting of nitro, chlorine, bromine, alkoxy of not more than 4 carbon atoms, alkyl of not more than 4 carbon atoms and phenyl; and R is selected from the group consisting of hydrocarbyl and substituted hydrocarbyl having up to four substituents, wherein the hydrocarbyl is selected from the group consisting of alkyl of not more than 12 carbon atoms, alkenyl of not more than 12 carbon atoms, cycloaliphatic having at least 4 and not more than 8 carbon atoms, benzyl and phenyl, and wherein the substituents on the hydrocarbyl are selected from the group consisting of chlorine, bromine, nitro, alkyl of not more than 4 carbon atoms, alkoxy of not more than 4 carbon atoms and phenyl.

The process of this invention by which the carbamides are prepared involves reacting oxalyl chloride with a substantially equimolar amount of an N-substituted carbamic acid ester of the defined configuration. The N-substituents can vary widely but the esterifying group must be one of the narrower scope to effect the formation of the new compounds. The reaction is conducted in an inert aromatic solvent medium, for example benzene, xylene, toluene, chloroxylene, chlorotoluene, 1,4-dichlorobenzene and other aromatic and halogen substituted aromatic hydrocarbons. The reaction mixture should be heated but temperatures as low as about 30° C. will effect a useful result. Higher temperatures, for example the reflux temperature of the chosen solvent medium, produce preferred rates of reaction. Temperatures as high as about 180° C. will be useful; however, decomposition of the product takes place if this temperature is exceeded.

When the reaction has been completed or has proceeded to a desired extent, the product can be separated from the solvent medium by the addition of a suitable non-solvent which is miscible with the solvent medium, for example n-hexane or any other aliphatic petroleum fraction. This reduces the solubility of the product in the solvent medium and causes precipitation of the product. The reduction in temperature also aids in the separation of the desired product. The solid product can be separated by filtration and purified, if desired, by recrystallization from a suitable solvent, for example acetone.

Further details of the procedure and the novel compounds so prepared are set forth in the following examples.

EXAMPLE 1

45 A solution of 22 gms. of methyl 3,4-dichlorocarbanilate and 12.7 gms. of oxalyl chloride in 50 ml. benzene was heated at reflux temperature for six hours. The product N-(3,4-dichlorophenyl)-N-carbomethoxyoxamyl chloride was separated from the benzene by the addition of 200 ml. of hexane to the cooled solution. Upon recrystallization from toluene white platelike crystals (M.P. 100.4 to 101.2° C.) were formed.

EXAMPLE 2

55 The procedure of Example 1 was repeated except that ethyl 3,4-dichlorocarbanilate was used in place of the methyl ester. The resulting product (M.P. 102–103° C.) 60 was found to have the structure

65

70

3
EXAMPLE 3

The reaction product of oxalyl chloride and n-propyl 3,4-dichlorocarbanilate was found to have a melting point of 56-57° C. and the structure

EXAMPLE 4

The phenyl ester of N-allylcarbamic acid was heated with oxalyl chloride in a toluene solution. The resulting product was found to have the structure:

EXAMPLE 5

Benzyl N-ethylcarbamate was heated at reflux temperature with oxalyl chloride in a 1,4-dichlorobenzene solution. After refluxing for three hours the product was identified as that of the structure:

EXAMPLE 6

Using the procedure of Example 1 oxalyl chloride was reacted with phenyl N-3,4-dichlorocarbanilate in a xylene solution. Heating at reflux temperature for four hours produced a reaction mixture which upon cooling and dilution with n-hexane produced a product of the structure:

EXAMPLE 7

The reaction at reflux temperature in a chlorotoluene solution between oxalyl chloride and 2-ethylhexyl carbanilate produced a product of the structure:

EXAMPLE 8

Using the procedure of Example 1 except that n-butyl N-cyclohexylcarbamate was used in place of the methyl 3,4-dichlorocarbanilate. The product was identified as N-carbobutoxy-N-cyclohexane oxamoyl chloride.

EXAMPLE 9

In a toluene solution oxamyl chloride and N-benzyl n-propylcarbamate were heated at 115° C. for 16 hours. The product was identified as N-benzyl-N-carbon-n-propoxy oxamyl chloride.

EXAMPLE 10

A xylene solution containing equal mols of oxamyl chloride and N-ethylmethylcarbamate was heated at reflux

for 10 hours. The product was identified as having the structure:

Useful compounds may also be prepared by reacting oxamyl chloride with other esters of N-substituted carbamic acids by the procedures above described to obtain the following:

Although the invention has been described with respect to specific modifications, it is not intended that the details thereof shall be limitations on the scope of the invention except to the extent incorporated in the following claims.

What is claimed is:

1. Compound of the formula

wherein R¹ is selected from the group consisting of hydrocarbyl and substituted hydrocarbyl having up to four substituents, wherein the hydrocarbyl is selected from the group consisting of primary alkyl of not more than 12 carbon atoms, benzyl and phenyl, and wherein the substituents on the hydrocarbyl are selected from the group consisting of nitro, chlorine, bromine, alkoxy of not more than 4 carbon atoms, alkyl of not more than 4 carbon atoms and phenyl; and R is selected from the group consisting of hydrocarbyl and substituted hydrocarbyl having up to four substituents, wherein the hydrocarbyl is selected from the group consisting of alkyl of not more than 12 carbon atoms, alkenyl of not more than 12 carbon atoms, cycloaliphatic having at least 4 and not more than 8 carbon atoms, benzyl and phenyl, and wherein the substituents on the hydrocarbyl are selected from the group consisting of chlorine, bromine, nitro, alkyl of not more than

4 carbon atoms, alkoxy of not more than 4 carbon atoms and phenyl.

2. Compound of claim 1 wherein R is primary alkyl of not more than 12 carbon atoms.

3. Compound of claim 1 which is N-3,4-dichlorophenyl-N-carbomethoxy oxamyl chloride.

4. Compound of claim 1 which is N-benzyl-N-carbo-n-propoxy oxamyl chloride.

5. Compound of claim 1 which is N-ethyl-N-carbo-benzoxy oxamyl chloride.

6. Compound of claim 1 which is N-(n-propyl)-N-carbophenoxy oxamyl chloride.

7. Compound of claim 1 which is N-ethyl-N-carboxy-methoxy oxamyl chloride.
